CLAIM

The ornamental design for the stackable low depth tray, as shown.

DESCRIPTION

FIG. 1 is a perspective view of a stackable low depth tray showing our new design;

FIG. 2 is a side view thereof;

FIG. 3 is an end view thereof;

FIG. 4 is a top plan view thereof; and,

FIG. 5 is a bottom plan view thereof.

The broken line showing of the bottom of the stackable low depth tray in FIGS. 6-10 forms no part of the claimed design.
